[57] **CLAIM**

The ornamental design for a combined apron and front wheel assembly for a handpowered palett truck, as shown and described.

DESCRIPTION

FIG. 1 is a perspective view from the front, top and side of a combined apron and front wheel assembly for a handpowered palett truck showing my new design;

FIG. 2 is an elevational view thereof from an opposite side;

FIG. 3 is a front elevational view thereof;

FIG. 4 is a rear elevational view thereof;

FIG. 5 is a top plan view thereof; and,

FIG. 6 is a bottom plan view thereof.

The broken lines illustrate the environment in which the assembly is used and forms no part of the claimed design.
